UNITED STATES PATENT OFFICE.

ERNEST H. PEABODY, OF PELHAM MANOR, NEW YORK, ASSIGNOR TO PEABODY ENGINEERING CORPORATION, OF NEW YORK, N. Y., A CORPORATION OF NEW YORK.

AIR REGISTER.

Application filed August 18, 1922. Serial No. 582,702.

My invention relates to air registers for admitting and controlling the flow of air, and particularly for use with apparatus for burning liquid or finely divided fuel. One aim of the invention is to make an air register of simple and cheap construction in which the air is easily controlled by means of doors arranged in the annular space formed between two cylindrical concentric surfaces, and of such design as to give the entering air a rotary motion.

Further features of my invention will be apparent from the following drawings:

Figure 1 is a longitudinal section through the air register as attached to the wall of the furnace.

Figure 2 is a section through the air register on the line 2—2 of Figure 1.

Figure 3 is a view of one of the air doors, showing the hinge strap.

Figure 4 is a side view or elevation of Figure 3.

Figure 5 is a detail of one of the doors, as arranged between the two cylindrical surfaces.

Figure 6 is a plan view of Figure 5 showing method of rotating the door and controlling its position.

Figure 7 is a modification which I employ. In the carrying out of my invention I employ a cylindrical member 1 which consists of a pipe or casting provided with a flange 2, which is fastened to the furnace front 3 by means of studs 4. The furnace front is lined with fire brick 5 having a suitable opening 6, through which the oil is injected into the furnace from the sprayer or fuel pipe 7. A second cylindrical surface 8 which laps cylinder 1, and concentric therewith, has a forward extension 9 properly curved to deliver the air to the space under the hollow cylinder 1. The extension 9 is provided with an extension or boss 11, which supports the sprayer or fuel pipe 7. The set screw 12 serves to hold the sprayer or fuel pipe in a fixed position. A series of holes is provided in the cylindrical surface 8 around its entire circumference, which receive the bolts 13. These bolts are tapped into a corresponding set of holes 14 in the cylindrical surface 1 and suitable pipe spacers or separators 15 are placed between the two cylindrical surfaces, holding them in definite relation to each other, the cylinder 8 overlapping the cylinder 1 by a suffi-

cient margin. By reason of the fact that the pipe spacers 15 are all made the same length, the cylinder 8 is held in a concentric position as regards cylinder 1. The bolts 13 pass through this pipe spacer and when screwed into the holes 14 serve to hold the two cylinders in this fixed concentric position. The number of bolts 13 is optional, dependent on the diameters of the cylinders 1 and 8. I have selected eight bolts in this construction, as shown in Figure 2. This number may be altered to suit the particular design of the register required. Corresponding in number with the bolts 8, suitable air doors 16 are provided and to each of these doors is attached a strap 17. The doors 16 are of sufficient width to cause one to overlap upon the other when assembled in the annular space formed between the walls of the cylinders 1 and 8.

The ends of these doors are preferably made radial to the concentric circles comprised in the edges of the door, which latter are thus made to conform to the curvature of the cylinders 1 and 8. Sufficient clearance is given to the doors so that they can swing around the pipe spacers 15 which act as hinges. The strap 17 is attached to the doors on a line which is radial to the surface of the inner and outer cylinders, and the ends of these straps are turned up at right angles to the surface of the door and provided with suitable openings 18, to fit the pipe spacers 15.

On the inner end, that is, the end toward the center of the two cylinders, the strap 17 has an extension 19 fitted with a slot 20. Resting on the exterior surface of the cylinder 1, there is a ring 21 which is movable around the periphery of the cylinder. The handle 22 is provided in order to move this ring. This handle is fitted with a thread at its inner end 23, so that it may be screwed into a suitable opening in the ring 21, and can be made to set up tightly on the surface of the cylinder 1, and serve as a set screw for holding the ring in any desired position. The ring 21 is fitted with a number of pins or tap bolts 24, corresponding in number with the number of doors, and equally spaced, as are the bolts and pipe spacers 13 and 15.

When assembled, the prolonged portion of the straps 17 extends over the ring 21 and the bolts 24 are arranged so that they fit

within the slot 20 in this prolonged portion of the strap. By reason of the fact that the pipe spacer 15 passes through the openings 18 in the strap 17 the doors may be rotated about these hinges by rotating the ring around the cylindrical surfaces 1, the slot 20 permitting of this rotation without any binding on the bolts 24. These doors may be held in a position which closes entirely 10 the annular space between the cylinders 1 and 8, or by rotating the ring they may be opened to any desired amount, and can be held in a fixed position, by screwing down the handle 22. It will be obvious that as 15 these doors are parallel to each other and may be set at an angle to the axis of the two concentric cylinders, the air on entering between these doors will assume a rotary motion around said axis. A suitable opening 20 25 is provided for inspection and lighting of the fuel, and other openings 26 may be provided for cleaning purposes if desired. All of these openings are provided with shutters for closing same when the register is 25 in operation.

In Figure 1, I show an embodiment of my invention so constructed that the heat of the furnace front is utilized to warm the air entering the combustion chamber and thereby 30 preventing a cold blast of air striking directly the flame. With this construction also there is no direct radiation from the furnace through the register doors as if the embodiment shown in Figure 7 is used. However 35 I do not wish to limit myself to either construction as it may be desirable to use either or a modification of either on account of contingencies arising in the actual installation. My invention consists of an annular 40 register with segmental doors overlapping and pivotally mounted between the two concentric surfaces forming the annular inlet.

I wish it distinctly understood that my air

register herein described and illustrated is in the form in which I desire to construct 45 it and that changes or variations may be made as may be convenient or desirable without departing from the salient features of my invention and I therefore intend the following claims to cover such modifications as 50 naturally fall within the lines of invention.

I claim:

1. In a fuel burning apparatus, an air register comprising inner and outer ring like members which overlap to form an extended annular air passage, bolts connecting said ring like members to hold them in spaced relation, a plurality of shutter members mounted to oscillate on said bolts, a ring like shutter operating member movably mounted on the inner ring member, and means for moving said operating member. 55

2. In a fuel burning apparatus, an air register comprising inner and outer ring like members having concentric portions which form an extended annular air passage, fixed means connecting said ring like members to hold them in spaced relation, a plurality of shutter members mounted on said means and movable to overlapping relation when closed, 60 a ring like shutter operating member mounted on the inner ring member, and means for moving said member. 65

3. In a fuel burning apparatus, an air register comprising a plurality of annular members having concentric portions forming an extended annular air passage, fixed means connecting said members to hold them in spaced relation and passing across said passage, a plurality of shutter members carried 70 by said means to oscillate thereon, an oscillating shutter operating member mounted on the inner ring member, and a handle for moving said last-named member. 75

In testimony whereof I affix my signature.

ERNEST H. PEABODY.
